(57) **CLAIM**

The ornamental design for a transaction card having triangular edge feature, as shown and described.

DESCRIPTION

The present application is filed contemporaneously with U.S. Design patent application Ser. No. 29/801,996, entitled Chipped or Chipless Transaction Card Having Trapezoidal Edge Feature, the entire disclosure of which is hereby incorporated by reference herein.

FIG. 1 is a perspective view of the first embodiment of the transaction card having triangular edge feature showing our design;

FIG. 2 is a plan view, the opposite plan view being a mirror image thereof;

FIG. 3 is an end view thereof

FIG. 4 is a perspective view of a second embodiment thereof;

FIG. 5 is a plan view, the opposite plan view being a mirror image thereof;

FIG. 6 is an end view thereof;

FIG. 7 is a perspective view of a third embodiment thereof;

FIG. 8 is a plan view, the opposite plan view being a mirror image thereof;

FIG. 9 is an end view thereof;

FIG. 10 is a perspective view of a fourth embodiment thereof;

FIG. 11 is a plan view, the opposite plan view being a mirror image thereof;

FIG. 12 is an end view thereof;

FIG. 13 is a perspective view of a fifth embodiment thereof;

FIG. 14 is a plan view, the opposite plan view being a mirror image thereof;

(Continued)

FIG. 15 is an end thereof;
FIG. 16 is a perspective view of sixth embodiment thereof;
FIG. 17 is a plan view, the opposite plan view being a mirror image thereof; and,
FIG. 18 is an end view thereof.
In the drawings, the broken lines shown depict environmental subject matter only and form no part of the claimed design
